DESIGN FOR A TOY

Frank De' Giovanni, San Francisco, Calif.

Application November 22, 1939, Serial No. 88,424

Term of patent 3½ years

To all whom it may concern:

Be it known that I, Frank De' Giovanni, a citizen of the United States of America, residing at San Francisco, in the county of San Francisco and State of California, have invented a new, original, and ornamental Design for a Toy, of which the following is a specification, reference being had to the accompanying drawing, forming a part thereof.

Fig. 1 is a side elevation of a toy, showing my new design;

Fig. 2 is a top plan view thereof;

Fig. 3 is a rear elevation thereof; and

Fig. 4 is a front elevation thereof.

I claim:

The ornamental design for a toy, substantially as shown.

FRANK DE' GIOVANNI.
